WINDOW STRUCTURE

Olaf L. Ware, Minneapolis, Minn.

Application May 24, 1930. Serial No. 455,387

2 Claims. (Cl. 20—11)

This invention relates to window structures and has relation more particularly to the parting, stopping and kindred strips comprised in such structures, and it is primarily an object of the invention to provide a strip of this kind which also provides effective protection against the weather and thus obviating the necessity of employing supplemental or independent weather stripping.

- 10 Another object of the invention is to provide a strip of this general character so constructed to afford means whereby, when in applied position, an effective guide or retaining medium is provided for a screen.
- 15 An additional object of the invention is to provide stripplings of this kind which materially reduce the cost of the window structure both as to material and labor and more especially as to the time required in finishing a window structure.

The invention consists in the details of construction and in the combination and arrangement of the several parts of my improved window structure whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:—

35 Figure 1 is a view in elevation illustrating a window structure constructed in accordance with an embodiment of my invention with screens in applied or working position;

40 Figure 2 is an enlarged detailed sectional view taken substantially on the line 2—2 of Figure 1;

Figure 3 is an enlarged detailed sectional view taken substantially on the line 3—3 of Figure 1;

45 Figure 4 is an enlarged fragmentary sectional view taken substantially on the line 4—4 of Figure 1;

Figure 5 is an enlarged fragmentary sectional view taken substantially on the line 5—5 of Figure 1.

50 As disclosed in the accompanying drawings, F denotes a frame structure of ordinary or preferred type and with which coacts the conventional sliding sashes S. Interposed between the upper and lower sashes S is a parting strip P. This strip P, as is particularly illustrated in

Figure 3 of the drawings, is made of a single sheet of metal and this sheet is bent to provide the central body portion with the side walls 1 of which being continued to provide the reverted flanges 2 which are adapted to be snugly received within suitably formed grooves or slots 3 in the jamb of the window. The space between the flanges 2 is free and unobstructed when the strip is unapplied.

The reverted flanges 2 are continued by the substantially perpendicularly related and outwardly disposed flanges 4 which have close contact with the outer face or surface of the jamb. These flanges 4 have their outer marginal portions formed to provide the reverted flanges 5 substantially at right angles to the flanges 4. Each of these flanges 5 is extended within a groove or slot 6 formed in the outer face of a stile 7 of a window sash whereby effective protection against outside weather conditions is obtained. In other words, it is to be noted that the strip P affords two important functions, namely, that of a parting strip and that of a weather strip.

In Figure 2 is also illustrated a strip P' similar to the strip P and which is operatively engaged with the crown piece 8 of the window frame.

Each of the frame jambs has engaged therewith for coaction with the upper sash S an outer stop strip, generally indicated as A. This strip is also made from a single sheet of metal and is formed to provide a central reverted flange 9 from the outer marginal portions of which are disposed in opposite directions the flanges 10 and 11. These flanges 10 and 11 are substantially at right angles to the flange 9 and have direct contact with the outer face of the frame jamb. The outer longitudinal margins of the flanges 10 and 11 are provided respectively with the reverted flanges 12 and 14 substantially at right angles thereto, the flange 14 being received within a suitably positioned groove or slot 15 formed in the stile of the upper sash S whereby further means are provided against the weather.

The strip A is also formed to provide a second reverted flange 16 which is substantially coplanar with the flange 9 and this flange, when the strip A is applied, enters a groove or slot 17 in the window jamb, thus further affording protection against outside weather.

Secured to the crown piece 8 of the frame in proper position is a second strip A' constructed in the same manner as the strip A.

The outside flanges 12 of the strips A, preferably at points below the meeting rails of the sashes S when closed, are provided with the cutouts or recesses 17 affording ready entrances 5 for the screen or ventilator sections C. Each of these screen or ventilator sections comprises a relatively thin metal framing 18 to which are suitably anchored or affixed the marginal portions of the screen fabrics or sheets 19. Each 10 of the sections C possesses sufficient inherent flexibility to permit the same to be readily placed within the runways afforded by the flanges 9, 10 and 12 of the strips A, and the framings 18 are of such thickness to permit one of the sections when necessary to slide into lapping relation with the second section. This 15 is of importance in initially applying the screen or ventilator sections as the first section applied will be forced up to the top portion of the window frame and then the second section will be forced upwardly to lap this first section sufficient to have the second section entirely enter within the runways whereupon the bottom section 20 is readily moved downwardly.

In order to assure the upper screen or ventilator section being maintained in such position I form the top member 20 of the top screen or ventilator section with a lateral or transverse incline so that as the top screen or ventilator 25 section is forced upwardly to the limit of its movement this member 20 will tightly or frictionally engage the flanges 12' and 9' of the strip A'. This engagement, however, offers no real resistance when it is desired to lower this top screen or ventilator section, as for example when it is desired to remove the same from applied position out through the recesses or cutouts 30 17.

When the screen or ventilator sections C are 35 in applied position it is to be understood that the adjacent frame members thereof will be in overlying relation as particularly illustrated in Figure 4.

While not illustrated, it is to be understood 40

that in connection with a window frame front stop strips may be used constructed substantially the same as the strips A and A' hereinbefore referred to.

From the foregoing description it is thought 80 to be obvious that a window structure constructed in accordance with my invention is particularly well adapted for use by reason of the convenience and facility with which it may be assembled and operated, and it will also be obvious 85 that my invention is susceptible of some change and modification without departing from the principles and spirit thereof and for this reason I do not wish to be understood as limiting myself to the precise arrangement and formation 90 of the several parts herein shown in carrying out my invention in practice except as hereinafter claimed.

I claim:—

1. A strip for a window frame made from a single sheet of metal and comprising a reverted flange insertible within a slot in the window frame, flanges at opposite sides of said first named flange and substantially at right angles thereto, said second named flanges having contact 95 with an outer face of a jamb, the outer longitudinal margins of the second named flanges being defined by outstanding flanges, one of said last named flanges intermediate its ends being provided with a notch to provide an entrance for a screen.

2. A strip for a window frame made from a single sheet of metal formed to provide a parting strip extending longitudinally thereof and at substantially the transverse center of the strip, reverted flanges immediately adjacent to the opposite sides of the parting strip for insertion within slots in the window frame, the space between said flanges being free and unobstructed, the outer longitudinal margins of the strip being defined by outstanding flanges disposed inwardly of the frame.
